UNITED STATES PATENT OFFICE

158,392

WATCH BAND CLASP

Jack Laufer, Brooklyn, N. Y., assignor to Cromwell Manufacturing Corporation, Brooklyn, N. Y., a corporation of New York

Application September 15, 1948, Serial No. 148,594

Term of patent 7 years

(Cl. D17—3)

To all whom it may concern:

Be it known that I, Jack Laufer, a citizen of the United States, residing at 1620 Avenue I, Brooklyn, New York, have invented a new, original, and ornamental design for a Watch Band Clasp, of which the following is a specification, reference being had to the accompanying drawing, forming part thereof, in which:

Fig. 1 is a perspective view looking down upon a clasp embodying my new design;

Fig. 2 is a top plan view thereof; and

Fig. 3 is a side elevational view of the clasp shown in Figs. 1 and 2.

I claim:

The ornamental design for a watch band clasp, as shown.

JACK LAUFER.
